UNITED STATES PATENT OFFICE.

GEORGE L. WALKER, OF NEW YORK, N. Y., ASSIGNOR TO AIR REDUCTION COMPANY, INC., A CORPORATION OF NEW YORK.

BLOWPIPE.

1,310,099.

Specification of Letters Patent. Patented July 15, 1919.

Application filed March 19, 1919. Serial No. 283,588.

To all whom it may concern:

Be it known that I, GEORGE L. WALKER, a citizen of the United States, residing at New York city, in the county of New York, 5 State of New York, have invented certain new and useful Improvements in Blowpipes; and I do hereby declare the following to be a full, clear, and exact description of the invention; such as will enable others 10 skilled in the art to which it appertains to make and use the same.

This invention relates to blowpipes employing combustible mixtures to produce high temperature flames for heating, welding 15 and cutting operations and has for its object the accomplishment of certain advantages in the operation of the blowpipe, among which is the prevention of "flashback" or ignition of the mixture within the 20 blowpipe structure.

Among other objects and advantages of my invention is the provision of blowpipe structures particularly adapted for operation in the manner hereinafter described to 25 accomplish the desired results.

These and other objects of my invention will be better understood by reference to the following specification when read in connection with the accompanying drawing 30 illustrating the preferred mechanical embodiments of my invention in which:

Figure 1 is a longitudinal section through a blowpipe constructed in accordance with my invention, and

35 Fig. 2 is a longitudinal section through another form of blowpipe embodying the same principles of construction but differing somewhat in mechanical details.

Blowpipes of the character hereinbefore referred to are customarily supplied with an oxidizing and a combustible gas, usually oxygen and acetylene. Heretofore it has been the accepted practice to admit the oxygen to the blowpipe at a gage pressure considerably higher than that of the acetylene.

I have discovered that advantageous results are possible where the initial pressure of the acetylene is equal to or greater than that of the oxygen and particularly where 50 the velocity of the acetylene at the point of mixture with the oxygen is equal to or higher than the velocity of the oxygen.

The primary difficulty which I propose to overcome through the practice of my invention is the result of the phenomenon

commonly called "flashback" in which the gaseous mixture becomes ignited and burns within the blowpipe structure. This phenomenon is dependent upon the velocity of flame propagation in the mixture issuing 60 from the tip and is influenced by the deposit of carbon within the discharge passage. Normally the velocity of the issuing mixture is maintained high enough to insure against flame propagation backwardly into the discharge passage. When, however, the discharge passage becomes partially obstructed as frequently occurs in practice, the velocity of the issuing gases is lowered and ignition of the mixture within the blowpipe structure frequently occurs.

I have discovered that where the velocities of the two gases at the point of mixing are maintained equal, or the velocity of the acetylene is slightly higher than that 75 of the oxygen, the tendency to "flashback" is substantially overcome and even when the discharge passage from the tip is partially obstructed, the velocity of flame propagation rearwardly in the discharge 80 passage is lowered sufficiently so that the decreased velocity of the issuing gases is sufficient to maintain the blowpipe in operation.

In general I ascribe the result noted to the 85 enrichment of the mixture under conditions of decreased velocity at the outlet through the preponderance of the velocity of the acetylene at the point of mixing. The same result is, however noted where the velocities of the two gases are substantially 90 equal and I believe that an explanation of the result may be predicated upon the fact that when the mixture is uniform and in the proportions for which the blowpipe is designed, the velocity of the issuing gases is 95 sufficient to overcome any tendency to flame-propagation rearwardly. In the normal operation of blowpipes as hereinbefore practised, any diminution of the velocity of 100 the gases in the discharge passage has resulted in an enrichment of the mixture in oxygen which permits of flame propagation at a higher velocity. Hence the increased velocity of flame propagation is balanced 105 against a lower velocity of the gases and a "flashback" occurs. In carrying out my invention, however, a decreased velocity of the gases in the discharge passage either does not effect the mixture, or permits a slight 110

enrichment in acetylene. The speed of flame propagation remains, therefore, constant or is slightly decreased and in any event is sufficiently low so that under usual conditions no "flashback" occurs.

When the pressure and velocity of the acetylene exceeds the pressure and velocity of the oxygen, as introduced to the blowpipe, I have noted a characteristic condition which 10 confirms my explanation of the reasons for the peculiar phenomenon above described. The neutral flame which is produced when the blowpipe is functioning properly presents a well defined cone. If the nose of the 15 blowpipe is brought into close relation with the work, so that the outlet is partially obstructed and then withdrawn, a momentary change is noted in the character of the cone, which becomes elongated and ragged. This 20 condition is characteristic of the presence of an excess of acetylene in the burning gases.

In carrying out my invention it is preferable that the velocity of the acetylene exceed that of the oxygen, although it may be 25 substantially equal thereto at the point where the two gases are mixed within the torch. This may be accomplished by providing passages of equal cross sectional area through which the two gases are brought together and by regulating the supply of acetylene to substantially the same or a slightly higher pressure than that of the oxygen. The acetylene passage may, however, be 30 slightly smaller in cross sectional area than the oxygen passage and the acetylene pressure may be slightly greater than that of the oxygen. There should be no enlargement of the outlet from the acetylene passage which would permit expansion of the 35 gas and consequent drop in pressure thereof before it mixes with the oxygen. Preferably the two passages are brought together at a relatively sharp angle, the cross sectional area of the mixing passage thus formed being less than the combined cross sectional 40 areas of the two passages. The two passages may, however, be arranged in parallel or substantially parallel relation and may deliver the respective gases to a mixing chamber. Various other structural embodiments 45 capable of utilization in the application of my invention may be devised and the invention is in fact applicable to many of the blowpipes well known and commonly used 50 in the art.

I have, however, illustrated in the accompanying drawing two forms of blowpipes which may be employed in carrying out my invention, the illustration being limited to 55 that portion of the blowpipes in which the mixing and discharge of the gases occurs. Referring to Fig. 1 of the drawing, 5 indicates a head having a central passage 6 which is preferably formed before the head 60 is bent to the shape indicated in the draw-

ing. A tip 7 having a discharge passage 8 is threaded or otherwise secured to the head 5. The rear-end of the tip 7 is preferably provided with a conical surface 9 cooperating with a corresponding seat 10 in the head to provide a gas tight joint which prevents escape of gases about the threaded connection. The discharge passage 8 is of smaller cross sectional area than the passage 6 and is preferably countersunk at 11 at a 75 relatively sharp angle so that no abrupt shoulder occurs at the junction of the two 80 passages.

The oxidizing and combustible gases are delivered to the head through two pipes 12 and 13 preferably concentrically arranged and adapted to deliver the gases to passages 14 and 15 formed in a filler 16 which is threadedly supported at the rear-end of the head 5. The passages 14 and 15 are substantially of parallel and equal cross sectional area and the gases are delivered therefrom to a frusto-conical chamber 17 communicating with the passage 6. As previously pointed out the acetylene passage 14 may be of slightly smaller cross sectional area than the oxygen passage 15 in which event, it would be necessary to maintain the acetylene at a slightly higher pressure than that of the oxygen. The two gases delivered 90 to the chamber 17 issue from their respective passages at substantially the same velocity or the acetylene may issue at a slightly higher velocity than the oxygen. The gases are mixed in a chamber 17 and passage 6 and 95 are delivered to the discharge passage 8 of the tip.

In Fig. 2 of the drawing, I have illustrated a slightly different form of my invention in which 20 indicates a head to which a tip 21 having a discharge passage 22 is secured in any suitable manner as for example, by threads 23 on the reduced portion 24 at the end of the tip. The head 20 is provided with converging passages 25 and 26 for oxidizing and combustible gases which are delivered to the passages through pipes 27 and 28 secured to the head. As in the preceding embodiment of the invention, the 105 passages 25 and 26 may be of substantially equal cross sectional area and the two gases may be delivered at the same pressure or the acetylene pressure may be somewhat higher 110 than the oxygen pressure. The passage 26 for acetylene may be slightly smaller in 115 cross sectional area than the passage 25 in which event a higher pressure will be maintained on the acetylene. The gases will mix in a frusto-conical chamber 29 formed by the juncture of the passages 25 and 26 and 120 will issue into this chamber at substantially the same velocity or with the velocity of the acetylene slightly higher than that of the oxygen.

Regardless of the particular structure em- 130

ployed in carrying my invention into practice, the accomplishment of the purpose follows the application of the principle of maintaining the velocities of the two gases substantially equal at the point where they mix, or providing acetylene at a velocity slightly higher than that of the oxygen at the point of mixture. Operation in the manner described effectually prevents "flash-back" and permits continuous operation which is highly advantageous because it conserves the time of the operator as well as the heat lost in the work while the torch is frequently relighted. This and other advantages of my invention render it highly desirable in practice and it will be understood that in the embodiments hereinbefore described, I have attempted merely to clearly explain the method of operation without intention to limit the invention to the specific mechanical structures illustrated.

Various changes may be made in the method of operation and in its application to blowpipes of varying construction without departing from the spirit and scope of the invention or sacrificing any of its material advantages.

I claim:

1. In the operation of blowpipes employed in heating, welding and cutting and burning mixtures of combustible and oxidizing gases, the method which comprises, causing the gases to commingle and thereby producing the combustible mixture and maintaining the ratio of velocities of the incoming gases so that the velocity of the combustible gas is not substantially lower than that of the oxidizing gas.
2. In the operation of blowpipes employed in heating, welding and cutting and burning mixtures of combustible and oxidizing gases, the method which comprises, causing the gases to commingle and thereby producing the combustible mixture and maintaining the ratio of the velocities of the incoming

gases so that the velocity of the combustible gas is at least substantially equal to that of the oxidizing gas.

3. In the operation of blowpipes, employed in heating, welding and cutting and burning mixtures of combustible and oxidizing gases, the method which comprises, causing the gases to commingle and thereby producing the combustible mixture and maintaining the ratio of the velocities of the incoming gases so that the velocity of the combustible gas is greater than that of the oxidizing gas.

4. In the operation of blowpipes employed in heating, welding and cutting and burning mixtures of combustible and oxidizing gases, the method which comprises, causing the gases to commingle and thereby producing the combustible mixture and maintaining the ratio of the velocities of the combustible and oxidizing gases so that enrichment of the mixture in oxidizing gas is prevented.

5. In the operation of blowpipes employed in heating, welding and cutting and burning mixtures of combustible and oxidizing gases the method which comprises, causing the gases to commingle and thereby producing the combustible mixture and maintaining the ratio of the velocities of the combustible and oxidizing gases so that the velocity of flame propagation in the mixture is prevented from exceeding the velocity of the mixture.

6. In the operation of blowpipes employed in heating, welding, cutting and like operations, and burning mixtures of combustible and oxidizing gases, the method which comprises, introducing combustible gas to the blowpipe at a pressure exceeding the pressure at which the oxidizing gas is introduced, causing the gases to commingle, and discharging the mixture.

In testimony whereof I affix my signature.

GEORGE L. WALKER.
